ATTORNEY.

UNITED STATES PATENT OFFICE.

DAVID G. LORRAINE, OF LOS ANGELES, AND WILLARD L. BOROUGH, OF FULLERTON, CALIFORNIA.

ADJUSTABLE-FLOW NIPPLE.

Application filed January 4, 1921. Serial No. 435,012.

To all whom it may concern:

Be it known that we, DAVID G. LORRAINE and WILLARD L. BOROUGH, citizens of the United States, residing, respectively, at Los Angeles, county of Los Angeles, and at Fullerton, county of Orange, State of California, have invented new and useful Improvements in Adjustable-Flow Nipples, of which the following is a specification.

It is the object of the present invention to provide an adjustable flow nipple particularly adapted to be employed in connection with oil wells. It has been found necessary to provide in the pipe line from an oil well, some regulating device for the flow of oil, and in the present invention we provide a regulating nipple the passage through which may be readily adjusted in size, so as to provide for any desired flow, the flow nipple at the same time being so constructed as to prevent cutting out of the same by the sand and the like passing through the pipe line.

It is a further object of the invention to provide a construction which will be inexpensive to manufacture and which will be durable and efficient in operation.

Further objects of the invention will be readily understood from the following description of the accompanying drawings, in which,

Figure 1 is a plan view of a nipple constructed in accordance with the invention.

Figure 2 is a longitudinal section through the same.

Figures 3 and 4 are transverse sections on the lines 3—3 and 4—4 of Figure 2.

In the drawings we have illustrated the flow nipple as employed in a pipe line having the pipe sections 1 and 2, the nipple being positioned between said sections and suitably attached thereto.

The nipple consists of a pipe 3 having a bore 4 and threaded ends 5 for detachably connecting the nipple to the pipe sections. The bore of the nipple is of uniform width and is rectangular in cross section. The top of the bore, shown at 6, is parallel to the longitudinal axis of the nipple, while the bottom of the same, shown at 7, is inclined so as to provide a bore of gradually tapering cross sectional area from one end of the nipple to the other.

The means employed for controlling the flow through the nipple consists of a wedge

shaped block 8, fitting snugly within the width of the bore, and also abutting against the top of the bore. The lower side of the block is inclined as shown at 9, so as to extend parallel to the base of the bore, and this inclined surface is spaced from base 7 so as to provide for the passage of fluid through the nipple.

It will be noted that the inclination of the underside of block 8 in conjunction with the inclined base of the nipple bore, provides a construction wherein longitudinal adjustment of the block in the bore of the nipple, will cause variations in the size of the opening provided through the nipple, and the device provides means for accurately adjusting block 8 so that the flow may be readily regulated in this manner.

As an instance of this arrangement, the pipe 3 may be provided with a transverse opening 11 communicating with bore 4 at the block 8, said opening being of sufficient length to permit of the desired longitudinal adjustment of the block which projects into said opening. The opening 11 is continued through a casing 12 projecting beyond pipe 3, and the end of this casing is provided with a threaded closure cap 13.

The portion of block 8 which projects into opening 11 is shown as a detachable member 14, having a removable top 15, and cooperating half bearings 16 formed in the adjacent surfaces of said member and its top. Bolts 17 are received through top 15 and member 14, so as to extend into block 8, and a longitudinally extending actuating rod 19 is received through bearings 16, and is held in position by passing the bolts 17 through the same. By this arrangement it will be seen that adjustment of rod 19 will move block 8 back and forth for regulating the size of the flow opening through the nipple.

The rod 19 extends at each end transversely beyond casing 12, and at one end is received in a closed guide bearing 20 projecting beyond said casing, and at the other end extends through a bearing 21 formed in the casing, and provided with packing 22 and a retaining nut 23.

The end of rod 19 extending beyond the packing bearing is threaded as shown at 24, and is slidably mounted in a lug 25 projecting from pipe 3. Nuts 26 are threaded upon the rod so as to abut against the re-

spective sides of lug 25, so that by adjustment of said nuts the rod 19 may be accurately longitudinally positioned and locked in any desired position.

5. A gauge is provided so that an opening may be formed in the nipple of any predetermined size, through adjustment of rod 19 and block 8 carried thereby. For this purpose a scale 27, preferably graduated in 10 sixteenths of an inch up to one inch, is formed upon pipe 3, and an indicator pin 28 carried by rod 19 cooperates with said graduations.

It will thus be seen that we have provided 15 a readily adjustable flow nipple, which is of simple but durable construction, and which is not subject to cutting out by sand and the like.

It is to be noted that while we have described the invention as employed in connection with the pipe line from an oil well, that the invention is not limited to this use, but is of general application, wherever it is desired to accurately regulate the flow of 25 a fluid.

It will be apparent that various changes may be made in the construction as thus described without departing from the spirit of the invention.

30. What is claimed is:

1. A flow nipple having a tapering bore, a longitudinally adjustable tapering regulating member received therein and cooperating therewith, said nipple having a transverse opening therein, a block in said opening and adjustable lengthwise of said nipple, and means for connecting said block to said regulating member.

2. A flow nipple having a tapering bore, 40 a longitudinally adjustable tapering regulating member received therein and cooperating therewith, said nipple having a transverse opening therein, a block in said opening and adjustable lengthwise of said nipple, 45 a longitudinally extending operating rod, and means for connecting said rod to said block and said block to said regulating member.

3. A flow nipple having a tapering bore, 50 a longitudinally adjustable tapering regulating member received therein and cooperating therewith, said nipple having a trans-

verse opening therein, a block in said opening and adjustable lengthwise of said nipple, a top for said block, said block and top having cooperating half bearings formed therein, a longitudinally extending operating rod received in said bearings, and connecting means extending through said top, rod, and block and into said regulating member.

55 60 65 70 75 80 85 90 95 100
4. A flow nipple having a tapering bore, a longitudinally adjustable tapering regulating member received therein and cooperating therewith, a longitudinally extending operating rod connected to said member and having a threaded end, a lug receiving said threaded end, and adjusting nuts threaded on said rod against the respective faces of said lug.

5. A flow nipple having a tapering bore, a longitudinally adjustable tapering regulating member received therein and cooperating therewith, a longitudinally extending operating rod connected to said member and having a threaded portion, a lug receiving said threaded portion, adjusting nuts threaded on said rod against the respective faces of said lug, an indicator pin in said rod, and a graduated scale cooperating therewith.

6. A flow nipple having a tapering bore and a longitudinally adjustable tapering regulating member received therein, said nipple having a transverse opening and a casing extending outwardly from the same, a block in said casing adjustable lengthwise of the nipple and casing, and means for connecting said block to said regulating member.

7. A flow nipple having a tapering bore and a longitudinally adjustable tapering regulating member received therein, said nipple having a transverse opening and a casing extending outwardly from the same, a block in said casing adjustable lengthwise of the nipple, an operating rod extending through the casing, and means for connecting said rod to said block and the latter to said regulating member, said casing having an opening for access to said connecting means.

In testimony whereof we have signed our names to this specification.

DAVID G. LORRAINE,
WILLEARD L. BOROUGH.
